UNITED STATES PATENT OFFICE.

FRANK CONRAD, OF EDGEWOOD PARK, PENNSYLVANIA, ASSIGNOR TO
WESTINGHOUSE ELECTRIC & MANUFACTURING COMPANY, A COR-
PORATION OF PENNSYLVANIA.

TRANSFORMER.

No. 829,572.

Specification of Letters Patent.

Patented Aug. 28, 1906.

Application filed January 20, 1904. Serial No. 189,911.

To all whom it may concern:

Be it known that I, FRANK CONRAD, a citizen of the United States, and a resident of Edgewood Park, in the county of Allegheny 5 and State of Pennsylvania, have invented a new and useful Improvement in Transformers, of which the following is a specification.

My invention relates to transformers for alternating electric currents; and it has for 10 its principal object the provision of a transformer to be employed in connection with protective apparatus for alternating-current circuits which will maintain a suitable operating voltage for such apparatus through a 15 wide variation of voltage in the main circuit.

In the accompanying drawings, Figure 1 is a diagram of one end of an alternating-current system of distribution in which my invention is utilized. Figs. 2 and 3 are side 20 elevations of two forms of core-plates which are embodied in my transformer, and Fig. 4 is a view in front elevation of a complete transformer constructed in accordance with my invention.

Protective apparatus such as that shown in Fig. 1 is described and claimed in an application, Serial No. 189,903, filed jointly by H. P. Davis and myself of even date here-with, and I will therefore here describe such 25 apparatus only so far as may be necessary to set forth the relations in which my present invention may be used.

Transformers 1 and 2 have their primary windings respectively connected in series relation in the line conductors 5 and 7 of a three-phase circuit 5 6 7, and similar transformers 3 and 4 have their primary windings respectively connected in series relation in the line conductors 8 and 10 of a three-phase 30 circuit 8 9 10, which operates in parallel with the circuit 5 6 7 to supply transformers 13 or other suitable translating devices. The secondary windings of the series transformers 1, 2, 3, and 4 are connected in series with windings 14 of special relay-transformers 15, each having a third winding 16, which is energized only when the currents in the two windings 14 are unequal or when one is reversed from its normal direction.

The windings 16 are connected in series with current-windings 17 of a special selective instrument 18 in the form of two wattmeters having their movable elements me-

chanically connected and adapted to move a contact member 19 against either the one or the other of the stationary contact-terminals 20 and 21. The effect of the latter action is to complete the circuit of the battery 22 through the one or the other of two circuit-breaker tripping-coils 23 and 24.

The voltage-windings 25 of the instrument 18 are supplied from the secondary windings 26 of a special transformer 27, which embodies my present invention. The primary winding 28 of the transformer 27 may be connected directly between two conductors of each of the distributing-circuits, as indicated at the top of Fig. 1, or it may be placed in series with the secondary winding 29 of a transformer, the primary winding 30 of which is connected between two conductors of each distributing-circuit, as indicated at the bottom of Fig. 1. The latter arrangement is preferable when the voltage of the distributing-lines is high, since a reduced voltage may be thus supplied to the windings 28 of the transformers 27.

The iron core of the transformer 27 comprises three legs 31, 32, and 33, the first-named two of which are provided, respectively, with the windings 26 and 28 and the last-named with an air-gap 34. The portion of the leg 31 which is surrounded by the winding 26 is reduced in width sufficiently to insure a cross-sectional area that is materially less than that of the remainder of the core, and the cross-sectional area of each of the legs 32 and 33 may be increased by placing additional punchings of the form shown in Fig. 3 on both sides of the previously-described punchings, substantially as shown in Fig. 4, which represents a complete transformer. The punchings may be made and assembled in any desired manner; but I have found it convenient to make punchings 35 of substantially **E** shape and of two dimensions as regards the length of the legs 31 and 32, as shown in Fig. 2, and punchings 36 of substantially **U** shape and also of two different dimensions as regards the length of the leg 32, as shown in Fig. 3, and to assemble them to form the core by alternately reversing either single punchings or groups of punchings having similar dimensions.

In the event of a short circuit on either 105 line the voltage would drop by reason of the

excessive current flowing, and if no device such as I have described were employed the voltage supplied to the instrument 18 would be too low to operate it. In my transformer 5 the iron of the reduced portion of the leg 31 is heavily saturated at the normal voltage of the line and the remainder of the flux induced by the primary winding 28 is forced across the air-gap 34 in the leg 33. If the 10 voltage impressed upon the primary winding 28 is greatly reduced, a smaller quantity of flux is forced across the air-gap 34, while that threading through the winding 26 is only 15 slightly reduced because of the smaller reluctance of that path. Hence the voltage impressed upon the windings 25 of the instrument 18 is varied but slightly, even though the drop on the line is considerable.

Evidently it is possible to use my transformer 20 as either a step-up or as a step-down transformer if it is desired to impress a higher or lower voltage on the windings of the instrument than can be derived from the main circuit; but it will generally be found advisable 25 to employ another transformer for such purpose, as has been already indicated. It is also obvious that my invention is capable of adaptation to other uses than I have described in which it is desired to maintain a 30 given operating voltage on any apparatus regardless of variations in the voltage of the main circuit.

I claim as my invention—

1. A transformer-core which provides two 35 magnetic circuits, one of a large cross-sectional area and interrupted by an air-gap, and the other of a much smaller cross-sectional area.

2. A transformer-core having three legs, 40 one of the outer legs having a smaller cross-sectional area than the other two and the other outer leg being interrupted by an air-gap.

3. A transformer-core which provides two 45 magnetic circuits, one unsaturated and of high reluctance and the other saturated and of low reluctance.

4. A transformer having primary and secondary windings and two magnetic circuits 50 passing through the primary winding, one unsaturated and of high reluctance, the other saturated, of low reluctance and surrounded by the secondary winding.

5. A transformer comprising primary and 55 secondary windings and an iron core having three legs, the primary coil being wound on the inner leg, the secondary on an outer leg having a smaller cross-sectional area than the other two, and the other outer leg being 60 interrupted by an air-gap.

6. A transformer having primary and secondary windings, a primary magnetic circuit of high reluctance and a primary magnetic

circuit of relatively low reluctance which is also the magnetic circuit for the secondary 65 winding.

7. A transformer having primary and secondary windings and two magnetic circuits of different reluctance, only one of which is common to both primary and secondary 70 coils.

8. A transformer having primary and secondary coils and two magnetic circuits of respectively high and low reluctance, the latter being common to both primary and secondary 75 coils.

9. A transformer having primary and secondary windings and a core that embodies a magnetic circuit which is common to both windings and an independent magnetic circuit 80 for the primary winding.

10. A transformer having primary and secondary windings and a core having three legs, one of which has an air-gap.

11. A transformer having primary and secondary windings and a core provided with three legs of different cross-section.

12. A transformer having primary and secondary windings and a core provided with three legs of different cross-section, the largest 90 leg being surrounded by the primary winding and the smallest leg being surrounded by the secondary winding.

13. In a system of distribution, the combination with a circuit-breaker having a trip-coil and a circuit-closing device having a current-coil and a voltage-coil, of a transformer for energizing the trip-coil comprising a core having three legs of different cross-section 95 one of which has an air-gap and primary and secondary coils on the other legs.

14. In a system of electrical distribution comprising parallel lines, the combination with circuit-breakers having connected trip-coils and a single circuit-closing instrument 105 for both coils, having two current-windings and two voltage-windings, series transformers between the current-windings and the parallel lines and transformers between the voltage-windings in the lines each of which 110 has two legs for the respective windings and a third leg having an air-gap but no winding.

15. A transformer comprising a core having three legs one of which is provided with an air-gap.

16. A transformer comprising a core having three legs and primary and secondary windings on two of said legs.

In testimony whereof I have hereunto subscribed my name this 11th day of January, 120 1904.

FRANK CONRAD.
